TAMPERPROOF CAN

George M. Ambrosius, Lakewood, Ohio, assignor
to The Standard Oil Company (Ohio), Cleve-
land, Ohio, a corporation of Ohio

Application June 2, 1936, Serial No. 83,098

1 Claim. (Cl. 220—76)

This invention relates to metallic shipping containers or cans, and it is among the objects of the invention to provide a container which can be sealed quickly and simply without necessity of resort to soldering or mechanical crimping, and which can not be unauthorizedly opened without destroying.

Other objects and advantages will appear as the description proceeds.

10 To the accomplishment of the foregoing and related ends, the invention, then, comprises the features hereinafter fully described, and particularly pointed out in the claim, the following description and the annexed drawing setting forth 15 in detail certain illustrative embodiments of the invention, these being indicative however, of but a few of the various ways in which the principle of the invention may be employed.

In said annexed drawing:—

20 Fig. 1 is a side elevational view, partly in section, showing an embodiment of the invention; Fig. 2 is a fragmentary similar view, showing parts in relation for assembly; Fig. 3 is a top plan view, partly in section; Fig. 4 is a similar view of a modification; Fig. 5 is an enlarged section taken on a plane substantially indicated by line V—V, Fig. 1; and Figs. 6, 7 and 8 are similar views of modifications.

25 The container body is suitably formed of sheet metal, as tin, sheet steel and the like, and may be closed at its lower end by a bottom which is seam bound or otherwise suitably permanently secured. The cover or closure for the open end, which is to be assembled in place after the can is filled with the goods to be packed, is similarly of suitable sheet metal, and the can body and cover are provided with coacting interlocking indentations such that when the cover is forced down into its final position, it snaps into place over the indentations. Snap fastening indentations have been known for a long time on containers such as tin boxes where the cover is to be snapped off in reverse movement, and the indents have been such as to permit opening thus as easily as closing. The present invention departs from such prior usages by providing a construction which prevents such removal, and the cover can in fact be detached only by destroying the parts. In the packaging of many articles, it is thus possible to fill the container and seal it by simple means and in the subsequent handling, shipping, etc., the cover can not be temporarily removed for the purpose of pilfering part of the contents, and in the final opening the container is destroyed to such an extent as to be impossible of

re-assemble. Goods which it is desired to insure against "bootlegging" re-filling are accordingly also particularly well safeguarded. In the embodiment of the invention in Fig. 1, the container body 2 has a suitable bottom closure 3 permanently secured, as by seaming, etc., and after the goods have been filled in, the cover 4 is snapped into place by the inter-locking indentations 5, 6. The container body is provided with a raised bead 7 beyond the edge 8 of the cover. 10 Such bead may extend transversely more or less completely about the container, as convenient. In the case of containers of square section as indicated in Fig. 2 in detail, the bead may extend across the greater expanse of each side, and 15 in the case of a container of circular section, as indicated in Fig. 4 it may completely encircle the circumference if desired. The bead however in any case is of sufficient extent to constitute a reinforcement or stiffening means rendering the 20 sheet metal wall correspondingly more resistant against inward bending. The bead may also provide stop-means for the edge of the cover. In the cover a receiving groove 10 is provided opposite the end edge of the container body, such that 25 the end edge 11 is received by and seats into the groove provided by the cover member. When the cover then is set in place, snapping over the inter-locking indentations, the body can not be pressed inwardly and deformed such as to release the 30 inter-locking indentations, this being prevented by the reinforcing beads 7 and by the receiving groove 10 holding the edge of the container body.

35 The precise detail of the inter-locking indentations may vary. As shown in Fig. 5, one convenient form is an outwardly projecting embossment 5 on the container body, and a mating embossment 6 on the cover. Instead of the embossments being stamped outwardly, they may be stamped inwardly, as shown in Fig. 6, in which 40 the embossment 5a is on the body, and the mating embossment 6a is on the cover, these being of rounded contour. Instead of having a rounded or smoothly curved contour as in the preceding forms, the embossments externally or internally 45 may be of more angular contour, as shown in Fig. 7, in which embossment 5b is on the container and embossment 6b is on the cover. Where the articles to be packed are of a character which 50 will not sift out, as is the case for instance with certain articles of hardware and metal which are advantageously packed and shipped as in the present manner, it is not necessary that the inter-locking indents be of the continuously extending form as illustrated foregoing, but may be stamped /

cutting through at the center of their lower margins 12, 13, Fig. 8, the relationship of the embossments and the action on assembly and after assembly being similar.

5 As thus clearly understood, the containers in unassembled condition are supplied at the point of filling, and are packed with the articles to be enclosed, whereupon the cover 4 is pressed down into position, the inter-locking indentations 6, 5, 10 etc., snapping together, and the end edge of the container body seating into the cover-groove 10. The cover is thereby positioned to remain, until destroyed in opening.

15 Other modes of applying the principle of the invention may be employed, change being made as regards the details described, provided the fea-

tures stated in the following claim, or the equivalent of such, be employed.

I therefore particularly point out and distinctly claim as my invention:—

A device of the character described comprising 5 a container body, a cover therefor and means for preventing intact removal of said cover, said means including a reinforcing bead on said container body to prevent bending therof, said bead lying beyond and adjacent said cover when it is 10 in place; a central depression in said cover; a narrow groove in said cover for tightly receiving the upper edge of said container body; and a plurality of spaced interlocking indentations on said container body and cover.

15 GEORGE M. AMBROSIUS.
